UNITED STATES PATENT OFFICE.

HENRY A. TUTTLE, OF TAUNTON, MASSACHUSETTS.

BRAKE MECHANISM FOR REVERSING-GEARING.

1,168,766.

Specification of Letters Patent. Patented Jan. 18, 1916.

Application filed October 15, 1914. Serial No. 866,820.

To all whom it may concern:

Be it known that I, HENRY A. TUTTLE, a citizen of the United States, residing at Taunton, in the county of Bristol and State of Massachusetts, have invented an Improvement in Brake Mechanism for Reversing-Gearing, of which the following is a specification.

This invention relates to brake-mechanism especially adapted for use in connection with reversing-gearing of the type represented in Letters Patent granted to me #901,664, dated October 20, 1908; and is intended as an improvement upon the brake-mechanism of Letters Patent granted to me #1,051,928, dated February 4, 1913, and generically considered is disclosed but not claimed in my application #713,020, filed August 3, 1912. In the brake-mechanism of said Patent #1,051,928, a pivoted actuating-means for the brake-members is employed which is connected by a link with a clutch actuating-lever, and such construction extends outward or upward for a considerable distance remote from the gearing, and necessitates arranging the actuating-means and link essentially at the outside of the inclosing case for the gearing, which is objectionable.

This invention has for its object the construction of a brake-mechanism and actuating-means therefor, which may be very compactly arranged with respect to the gearing, and may be easily connected with the clutch actuating-lever, and may be inclosed by the case which incloses the gearing, yet is very strong and durable, and may be easily operated.

Generally speaking my improved form of brake-mechanism comprehends a horizontally arranged and longitudinally movable cam-bar, and a pair of semi-circular brake-members arranged for rocking engagement with each other at their lower ends, and having at their upper ends engaging-portions and guide-ways for said cam-bar, permitting longitudinal movement of said cam-bar, whereby said brake-members are operated, and also guiding and supporting the cam-formed end-portion of said bar. The cam-faces on the cam-bar are arranged to engage the engaging-portions of the brake-members when said bar is moved in one direction, and to disengage said engaging-portions when said bar is moved in the other direction, and said cam-faces are so

arranged on the bar as to admit of longitudinal movement of the bar for a predetermined distance without engaging said engaging-portions, thereby admitting of a movement of the clutch actuating-lever into other positions than those designed for operating the brake-mechanism, as for instance, into neutral and into clutch-engaging position.

Figure 1, is a side elevation of a reversing-gearing having brake-mechanism embodying this invention. Fig. 2, is a plan view of the same. Fig. 3, is an end-elevation of the brake-members. Fig. 4, represents enlarged fragmentary views of the upper end-portion of the brake-members having engaging-portions embodying this invention. Fig. 5, represents plan views of the fragmentary-portions shown in Fig. 4, the engaging-portion of one of the members being omitted. Fig. 6, is a detail view of the engaging-portion which is removed from one of the brake-members of Fig. 5.

The reversing-gearing to which my invention is herein shown as applied, is similar to that of my application for Letters Patent Serial #629,596, filed May 26, 1911, which is an improvement upon the gearing of the aforesaid Letters Patent #901,664, and 71 represents the sliding-collar on the shaft *e*, to which is connected the operating-mechanism for the clutch, and 76 is a forked arm engaging means arranged on said collar, and 79 is the pivot-shaft for the actuating-lever to which said forked arm is connected. As said shaft 79 is oscillated, the sliding-collar is moved longitudinally for the purpose of operating the clutch. The brake-mechanism herein employed, by which a reverse rotary motion is obtained, comprises semi-circular brake-members 12, and 14, similar to those shown in my aforesaid Patent #1,051,928, said members being arranged for rocking engagement with each other at their lower ends.

The member 14 has at its upper end-portion, a pair of ears 20—20, see Fig. 5 arranged with a space between them, and each ear 20 has an elongated transverse passage 21 through it, and a vertically arranged pin 22, with or without a roll 23 thereon, arranged at the forward end of each passage, leaving an unobstructed space between the periphery of the roll on said pin and the rear end of the passage. These passages 21—21 are arranged in alinement.

The member 12 has at its upper end-portion a pair of flat-surfaced portions 30—30, see Fig. 5 which are arranged opposite the ears 20—20, over which said ears extend, when the two members 12 and 14 are oscillated and drawn toward each other, said portions 30—30 thus serving as bearing-portions beneath said ears. Said member 12 also has at its upper end-portion, between said bearing-portions 30—30, a channeled-portion 31, which is made of a width substantially corresponding to the space between the ears 20—20, and of a length to extend forward for a short distance, thereby to enter said space when the two members are drawn toward each other. In the channel of said portion 31 an elongated block 32 is arranged, see Fig. 6 which substantially corresponds in length and width with the channel, but is made of a thickness much greater than the depth of the channel, thereby to extend above the sides of the channel, and said block has at its rear end an externally screw-threaded pin 33, which extends through a hole in an ear 34, arranged at the rear end of the channel and which projects upward, and a nut 35 is arranged on the screw-threaded portion of said pin, thereby to hold the block 32 in place in the channel, and to adjust its position. Said block 32 has an elongated transverse passage 36 through it, similar to the transverse passages 21, and a pin 37 is arranged vertically at the forward end of said passage, with or without a roll 38 thereon, leaving an unobstructed space in rear of the periphery of a roll on said pin. Said passage 36 is arranged in the block 32 above the tops of the sides of the channel. When the two brake-members are arranged in their normal positions, free from engagement with the cylindrical-member of the gearing, their upper end-portions are arranged in coöperative relation, the ears 20—20, extending over the bearing-portions 30—30, and the block 32 entering the space between said ears, and the unobstructed space of the transverse passage 36 is approximately in alinement with the unobstructed spaces in the passages 21—21, thereby to admit of the cam-formed end-portion of a cam-bar being extended through or arranged in said passages, as represented in Fig. 2.

40 represents the cam-bar, which is horizontally arranged, and is made quite long, and is connected at one end with a clevis 41, which is loosely connected by a pin 42, with a short arm 43 secured to the pivot-shaft 79, or it may be otherwise connected with said shaft, or in fact otherwise connected with the means employed for operating the clutch. The other end of said cam-bar has cams arranged along each edge (see Fig. 2) for engagement respectively with the rolls 23—23 and 38, which rolls, as here shown, serve as

and constitute engaging-portions. Referring more specifically to said cam-formed end-portion of the bar, one edge of the bar has two recesses, and the other edge has one recess, and all of said recesses are similarly formed, each recess comprising an elongated portion 45, the bottom of which engages the adjacent roll, but exerts thereupon no substantial pressure, at least not sufficient to move the roll bodily to oscillate the brake-members, hence permits of a longitudinal movement of the bar independently of the brake-members, and also comprising a depression 46, in continuation of said elongated portion 45, which likewise permits of a longitudinal movement of the bar without bodily moving the roll, and also comprising an upwardly inclined portion 47, which serves as a cam, which, when brought into engagement with the adjacent roll moves said roll bodily, thereby to draw the two brake-members toward each other, and causing them to engage the cylindrical-member of the gearing which they embrace, and restrain said member from rotation. Longitudinal movement is imparted to the bar by a movement of the clutch-actuating means with which it is connected, but such connection, however, is for the purpose of enabling the same actuating-member to be employed to operate both the clutch and the brake. As said bar is arranged in the passages 21 and 36, it is supported and guided, and, thereby held in position for engagement with the rolls when moved.

As here shown, the pivot-shaft 79 is designed to occupy three different positions, as represented by dotted lines, Fig. 1, and when moved into the dotted line position indicated at the extreme right, the cam-bar will be moved in a corresponding direction far enough for its cams to engage the engaging-portions of the brake-members, thereby to move said brake-members into engaging position. When said pivot-shaft 79 is moved into the middle or vertical dotted-line position, the cam-bar is correspondingly moved far enough for its cams to disengage the engaging-portions of the brake-members, thereby to permit said brake-members to disengage the cylindrical-member. This is the neutral position; and with the parts in this position the rolls enter the depressed portions or recesses 46 at the bottoms of the inclined portions. These recesses 46 are provided particularly for the purpose of holding the cam-bar against longitudinal vibration, which is attained by the resiliency of the brake-members exerting their pressure thereupon. When said pivot-shaft 79 is moved into the dotted-line position at the extreme left, the cam-bar is correspondingly moved far enough for the clutch to be operated, and during such movement its cams move away from the rolls and the rolls fol-

low along the elongated portions of the recesses in the cam-bar. It will be observed that said cam-bar, when arranged horizontally, as here shown, and made movable in a longitudinal direction to operate the brake-members, occupies a position close to the gearing, and may be easily arranged within an inclosing case for the gearing, yet is easily operated, and is very strong and durable.

10 I claim:

1. A reversing-gearing and brake-mechanism therefor consisting of a pair of pivoted brake-members having engaging portions, a longitudinal movable bar arranged horizontally with respect to the gearing, a pivoted actuating-lever for the clutch actuating-mechanism of the gearing to which one end of said bar is loosely connected, said bar having at its other end recesses to receive the engaging-portions of the brake-members, each recess comprising an elongated portion and an inclined portion, the elongated-portions being arranged to permit longitudinal movement of the bar without exerting pressure upon the engaging-portions, to enable the actuating-lever to be moved to operate the clutch-mechanism, and the inclined-portions being arranged to act to move the 30 engaging-portions to operate the brake-members.

2. A reversing-gearing and brake-mechanism therefor comprising a pair of brake-members having engaging-portions, a horizontally-arranged bar adapted for longitudinal reciprocation, a pivoted actuating-lever for the clutch-mechanism to which one end of said bar is loosely connected, the other end of said bar having recesses, each recess having an elongated portion and an inclined portion, the engaging-portions of the brake-members normally occupying positions in the recesses substantially at the junction of the engaging-portions and inclined-portions, so that when the bar is moved in one direction from normal, said engaging-portions will engage the inclined-portions, and will be moved to operate the brake-members, and when the bar is moved in the other direction from normal, said engaging-portions will remain at rest.

3. The brake-mechanism for reversing-gearing herein described, consisting of a pair of brake-members movable toward and from each other, having aligned guiding and supporting means provided with engaging-portions, a sliding-bar arranged for connection with the clutch-mechanism of the gearing, said bar having its end-portion guided and supported by said means, and having recesses in its end-portion to receive said engaging-portion, each recess comprising an elongated-portion and an inclined-portion, the elongated-portions permitting longitudinal movement of the bar without exerting

pressure upon the engaging-portions, and the inclined-portions acting to move the engaging-portions to operate the brake-members.

4. The brake-mechanism for reversing-gearing herein described, consisting of a pair of brake-members arranged for rocking engagement with each other at their lower ends, and having engaging-portions at their upper ends, and a longitudinal movable bar arranged for connection with the clutch actuating-mechanism of the gearing, said bar having recesses in its edges for the engaging-portions of the brake-members, each recess comprising an elongated-portion and an inclined-portion, the elongated-portions of the recesses permitting longitudinal movement of the bar without exerting pressure upon the engaging-portions, and the inclined-portions acting to move the engaging-portions to rock the brake-members.

5. The brake-mechanism for reversing-gearing herein described, consisting of a pair of brake-members arranged for rocking engagement with each other at their lower ends, and having engaging-portions at their upper ends, and a longitudinal movable cam-bar arranged for connection with the clutch actuating-mechanism of the gearing, said bar having recesses in its edges for the engaging-portions of the brake-members, each recess comprising an elongated-portion, a depression, and an inclined-portion, the elongated portions and the depressions of the recesses permitting longitudinal movement of the bar without exerting pressure upon the engaging-portions, and the inclined-portions acting to move the engaging-portions to rock the brake-members.

6. The brake-mechanism for reversing-gearing herein described, consisting of a longitudinally movable horizontally disposed cam-bar arranged for connection with the clutch-actuating-mechanism of the gearing, a pair of semi-circular oscillating brake-members, one of said members having one or more ears with transverse passages and engaging-portions arranged in said passages, and the other brake-member having an ear with a transverse passage and an engaging-portion arranged in said passage, all of said passages being adapted to be arranged in alinement to receive the cam-formed end-portions of the cam-bar, longitudinal movement of said bar causing the cam faces thereon to engage said engaging-portions and thereby move the brake-members.

7. The brake-mechanism herein described for reversing-gearing, consisting of a pair of brake-members arranged to embrace a cylindrical-member of the gearing, one of said members having one or more ears adapted to extend over the other member and formed with a transverse passage and hav-

ing a roll arranged in said passage, and the other member having an adjustable block with a transverse passage and a roll arranged in said passage, all said passages adapted to be arranged in alinement, and a longitudinally movable cam-bar extended through said passages for engagement with said rolls, said bar being connected with the clutch actuating-mechanism of the gearing.

10 8. The brake-mechanism herein described for reversing-gearing consisting of a pair of brake-members arranged to embrace a cylindrical-member of the gearing, one of said members having one or more ears adapted to extend over the other member and formed with transverse passages and having rolls arranged in said passages, and the other member having an adjustable block

with a transverse passage and a roll arranged in said passage, all said passages being arranged in alinement, and a longitudinally movable cam-bar arranged in said passages for engagement with said rolls, said bar being connected with the clutch actuating-mechanism of the gearing, said bar having elongated recesses formed in its edges terminated at one end by inclined portions, which latter serve as cams.

20 In testimony whereof, I have signed my name to this specification, in the presence of two subscribing witnesses.

25 HENRY A. TUTTLE.
